Primary Examiner — Sandra Snapp*Assistant Examiner* — Mehri Bajoul*(74) Attorney, Agent, or Firm* — Leong C. Lei(57) CLAIM

The ornamental design for a two-player pinball machine, as shown and described.

DESCRIPTION

FIG. 1 is a perspective view of a two-player pinball machine showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a rear perspective view thereof.

The broken lines shown represent portions of the two-player pinball machine that form no part of the claimed design.
